UNITED STATES PATENT OFFICE.

NORMAN W. STORER, OF PITTSBURG, PENNSYLVANIA, ASSIGNOR TO WESTINGHOUSE ELECTRIC & MANUFACTURING COMPANY, A CORPORATION OF PENNSYLVANIA.

MEANS FOR CONNECTING CONDUCTORS TO COMMUTATOR-BRUSHES.

No. 910,243.

Specification of Letters Patent.

Patented Jan. 19, 1909.

Application filed April 4, 1906. Serial No. 309,892.

To all whom it may concern:

Be it known that I, NORMAN W. STORER, a citizen of the United States, and a resident of Pittsburgh, in the county of Allegheny and State of Pennsylvania, have invented a new and useful Improvement in Means for Connecting Conductors to Commutator-Brushes, of which the following is a specification.

My invention relates to commutator brushes for dynamo-electric machines, and it has for its object to provide improved means for securing conductors thereto.

It has been proposed by another than myself to provide the outer end of a commutator brush with two or more cavities and to cover the end of the brush with a plate from which split pins or other resilient studs project into the cavities, a flexible conductor being connected to the plate in a suitable manner. With such a structure, however, it is necessary that the distances between the cavities and the pins be exactly equal and that the pins be parallel, or else difficulty will be experienced in applying the plate to the end of the brush, and for these reasons also the parts may not be readily made interchangeable. I accordingly propose to provide but a single cavity in the outer end of the brush and to provide one or more recesses in the faces of the brush, in which projecting portions of the plate may be located in such manner as not to interfere with the free movement of the brush within a suitable holder therefor. With such a structure, the parts may be made interchangeable without the exercise of extraordinary care in drilling the cavity in the outer end of the brush or in securing the split pin or resilient wedge to the end plate, and the plate may be readily applied to the end of the brush without difficulty.

Figure 1 of the accompanying drawing is a view, in side elevation, of a commutator brush embodying my invention. Fig. 2 is a view, in end elevation, of the brush shown in Fig. 1; and Fig. 3 is a view of a modified structure from that shown in Figs. 1 and 2.

A commutator brush 1 that is composed of carbon or other suitable material is provided with a cavity 2 in its outer end, into which a split pin 3 or other suitable resilient wedge projects. The pin 3 is riveted or otherwise secured to an end plate for the brush having lips or projections 4 that are

bent downwardly into correspondingly located recesses 5 in the face of the brush, so that no portions of the plate extend beyond the faces thereof. A lug 6, that is secured to the upper side of the end plate is provided with a cavity 7, in which the end of a flexible conductor 8 is soldered or otherwise secured.

The split pin or resilient wedge makes good electrical contact with the walls of the cavity 2 and also serves to retain the end plate in position, the lips or projections 4 serving to prevent turning or lateral displacement of the plate. The lips or projections 4 may engage the same face of the brush, as shown in Figs. 1 and 2, or they may be provided upon opposite edges of the end plate so as to engage opposite faces of the brush, or, if desired, they may engage the ends of the brush. Thus a detachable connection to the brush is provided and the upper end of the brush is protected from wear or injury because the end plate serves as a wearing piece with which a spring-pressed arm or other part of a suitable holder for the brush may engage.

I claim as my invention:

1. The combination with a commutator brush having a cavity and a recess, of a plate that covers the cavity and has a portion that is bent into the recess with its outer surface flush with the brush surface, and an inherently expanded stud projecting from the plate and located in the cavity.

2. The combination with a commutator brush having a cavity and a recess, of a plate that covers the cavity and has a portion seated completely within the recess, and an inherently expanded stud projecting from the plate and located in the cavity.

3. The combination with a commutator brush having a cavity and recesses, of a plate that covers the cavity and has portions that are seated completely within the recesses, and an inherently expansible stud that projects from the plate into the cavity and is self-expanded therein.

4. The combination with a commutator brush having an end cavity and side recesses, of a plate that covers the cavity and has portions that are contained within the recesses, and a resiliently expansible stud that projects from the plate into the cavity and is self expanded therein.

5. The combination with a commutator

brush having an end cavity and side recesses, of a plate that covers the cavity and has portions that are seated in the side recesses and are flush with the side faces of the brush, and 5 a resiliently expansible stud that projects from the plate into the cavity and is self expanded therein.

In testimony whereof, I have hereunto subscribed my name this 30th day of March, 1906.

NORMAN W. STORER.
